UNITED STATES PATENT OFFICE.

WILLIAM J. KENELY, OF ELIZABETH, NEW JERSEY.

MEANS OF ESCAPE FROM SUBMARINES.

1,152,420.

Specification of Letters Patent.

Patented Sept. 7, 1915.

Application filed December 5, 1914. Serial No. 875,649.

To all whom it may concern:

Be it known that I, WILLIAM J. KENELY, a citizen of the United States, and a resident of Elizabeth, in the county of Union 5 and State of New Jersey, have invented a new and Improved Means of Escape from Submarines, of which the following is a full, clear, and exact description.

This invention relates to submarine navigation, and has particular reference to safety 10 appliances for submarine boats.

Among the objects of the invention is to provide a means of escape for the occupants of a standard submarine boat.

15 More definitely stated, I provide for a submarine boat substantially watertight compartments adjacent the top or any other convenient wall of the structure in which all of any number of the occupants of the vessel 20 may congregate in the event of accident or disaster incapacitating the propelling or controlling means for the vessel, and from which such occupants may set themselves free from the stranded vessel and float to 25 the surface of the water in life preservers or otherwise.

The foregoing and other objects of the invention will hereinafter be more fully described and claimed and illustrated in the 30 drawings forming a part of this specification, in which like characters of reference indicate corresponding parts in all the views, and in which—

Figure 1 is a side elevation of a diagrammatic representation of a submarine boat furnished with my improvement, parts of the same being broken away; Fig. 2 is an enlarged vertical sectional view of the immediate improvement; Fig. 3 is a bottom 40 plan view of the top of the compartment with the doors closed; Fig. 4 is a sectional detail on the line 4—4 of Fig. 3; Fig. 5 is a similar detail on the line 5—5 of Fig. 2; and Fig. 6 is a sectional detail on the line 45 6—6 of Fig. 3.

The several parts of this device may be made of any suitable materials, and the relative sizes and proportions, as well as the general design of the mechanism, may be 50 varied to a considerable extent without departing from the spirit of the invention hereinafter more fully described and specifically claimed.

Referring more particularly to the drawings, I show at 10 the main part of the hull

of a submarine boat, the top or upper deck of which is indicated at 11. At 12 is shown a compartment within the hull 10 and shown preferably located just below the deck 11 and of a size or capacity to accommodate 60 all or part of the crew at one time. This compartment 12 is designed to be watertight, but in the event of accident or otherwise, should the walls become distorted and cause a leakage to take place, a pump, as indicated at 13, may be employed to discharge any accumulation of water from the interior thereof. The pump may be located in any part of the interior of the compartment and may be used either for discharging water 70 which may leak into the compartment or it may be used to discharge water that has been intentionally flooded into the compartment.

At 14 I show the air tank through which 75 fresh air, oxygen or the like may be supplied to the interior of the compartment through a pipe 15, the same being controlled by any suitable valve 16. The air tank 14 may be understood in some instances as 80 representing any suitable form of air pump which may be utilized to discharge foul air from the interior of the compartment and replace it with fresher air from the main portion of the submarine vessel. 85

One or more doors 17 may be provided through the deck 11 to give access to the interior of the compartment 12. In this case two of these doors are employed, each hinged at 18 to the deck and adapted to 90 swing downwardly or inwardly around such hinge. One of the doors 17 overlaps the other along the free edges thereof as shown at 19, and the meeting edges of the doors and the deck frame surrounding the same are preferably corrugated and provided with a packing material indicated at 20. See Figs. 5 and 6. Any suitable means may be provided to lock the doors rigidly shut under normal conditions. Among these means I 95 employ a plurality of lag bolts 21 operated through the edges of the doors into the frame and also through the adjacent or overlapping free edges of the doors along the ridge 19. I also provide for the portions of the doors remote from the hinges 18 a pair of dogs 22 pivoted at 23 and hooking under the ends of that door which overlaps the other. Said dogs are held from rotation on their pivots by means of keys or wedges 100

105

110

driven between the same and rigid lugs 25 extending below the under surface of the deck.

At 26 I show a valve controlled inlet for 5 admitting water into the compartment from the exterior of the ship. At 27 I show a pressure gage which will indicate the degree of atmospheric pressure within the compartment at any time.

10 At 28 I show a door which typifies any suitable means to gain access to the interior of the compartment from the main part of the vessel, the same being equipped with suitable hinged and fastening devices. The 15 meeting edges of the door 28 and its frame are also preferably packed with a gasket 20 fitted in corrugated opposed surfaces.

The operation of the device may be briefly described as follows: In the event of accident or disaster disabling the controlling mechanism for the vessel, the occupants thereof may assemble within the compartment 12 and close the door 28, or if there are more than one compartment, some of the 20 men may assemble in one and some in the other. When within the compartment the men will apply their life belts or the equivalent, and then will flood the compartment through the nozzle 26 to a depth substantially up to their chins or as high as may 25 be necessary to avoid injury to themselves when the doors 17 are opened. With the dogs 22 in holding position, the lag bolts 21 may be removed by some of the men with 30 suitable tools, and then the keys or wedges 24, upon being knocked out of place, the dogs will be free to swing on their pivots allowing the doors to swing inwardly either by their own weight or by the same in conjunction with the external water pressure. 35 If, however, either of them should stick, it may be started by the driving of one or more wedges 29 between the same and the deck 11. It will be understood, of course, that by the provision of means to supply 40 fresh air to the upper portion of the compartment in which the men are working, ample time will be afforded for the manipulation of the devices just described. After 45 the doors are opened, the men may escape readily from the compartment 12, any suitable number of bars or hand rails 30 being provided to assist them in controlling their movements within the compartment and escape therefrom.

I claim:—

1. In a submarine boat, the combination of a compartment of a size suitable to hold the entire crew, means for the crew to have access to the interior of the compartment, 60 a doorway leading from the compartment to the exterior of the boat, a door hinged along one edge to the frame of the doorway and adapted to open inwardly, a series of lag bolts passing through the edge of the 65 door and into the structure surrounding the doorway for holding the door shut under ordinary conditions, auxiliary holding means serving to temporarily hold the door shut after the lag bolts are removed, said auxiliary holding means comprising a dog pivoted opposite each end of the door and each having a point extending beneath the adjacent end of the door, and a wedge acting directly against the dog on that side of its 70 pivot opposite the engaging point, substantially as set forth.

2. In a submarine boat, the combination of a substantially airtight compartment adjacent the top of the boat, a doorway leading from the compartment to the exterior of the boat, a pair of doors hinged at their opposite edges along opposite sides of the doorway and overlapping each other at their adjacent edges, a plurality of lag bolts passing directly through the doors and locking the same to each other at their overlapping edges and to the framework surrounding the doorway holding the door shut, a pair of dogs pivoted to the doorway frame opposite the ends of the overlapping portions of the doors, each dog including a point extending to one side of the vertical plane of its pivot and adapted to swing downwardly under the action of the doors, a rigid lug secured to the doorway frame adjacent but spaced from each of the dogs, and a wedge driven normally between said lug and the adjacent door serving to hold the dog in position to temporarily sustain the doors 100 shut after the lag bolts aforesaid are removed.

In testimony whereof I have signed my name to this specification in the presence of two subscribing witnesses.

WILLIAM J. KENELY.
